COACH

Albert A. Boca, Grosse Pointe, Mich., assignor to General Motors Corporation, Detroit, Mich., a corporation of Delaware

Application March 4, 1950, Serial No. 8,322

Term of patent 14 years

(Cl. D14—3)

To all whom it may concern:

Be it known that I, Albert A. Boca, a citizen of the United States, being a resident of Grosse Pointe, State of Michigan, have invented a new, original, and ornamental Design for a Coach, of which the following is a specification, reference being made to the accompanying drawing, forming a part thereof.

In the drawing:

The dominant features of my design are shown in solid lines in each of the above figures.

I claim:

The ornamental design for a coach, substantially as shown and described.

ALBERT A. BOCA.
